UNITED STATES PATENT OFFICE.

AGNAR KAARBO, OF CLEVELAND, OHIO.

WELDED STEEL BARREL AND METHOD OF MAKING SAME.

1,313,387.

Specification of Letters Patent. Patented Aug. 19, 1919.

Application filed February 19, 1919. Serial No. 277,996.

To all whom it may concern:

Be it known that I, AGNAR KAARBO, a subject of the King of Norway, and a resident of Cleveland, county of Cuyahoga, 5 and State of Ohio, have invented a new and useful Improvement in Welded Steel Barrels and Methods of Making Same, of which the following is a specification, the principle of the invention being herein explained 10 and the best mode in which I have contemplated applying that principle, so as to distinguish it from other inventions.

The subjects of the present invention are steel barrels or receptacles and the method 15 of making the same. The objects are the provision of a suitable barrel or receptacle which may be manufactured cheaply and easily, and which is strong and durable. The present invention relates more specifically 20 to barrels which are formed in halves and then united to form the finished receptacle, the method of forming the joint and the construction thereof being of particular importance. To the accomplishment of 25 the foregoing and related ends, said invention, then, consists of the means hereinafter fully described and particularly pointed out in the claims.

The annexed drawing and the following 30 description set forth in detail one method and one product exemplifying my invention, such disclosed procedure and product constituting, however, but one of various applications of the principle of my invention.

35 In said annexed drawing:—

Figure 1 is a longitudinal section through a barrel showing the present construction; Fig. 2 is a section of a detail showing the two halves of the barrel after the first operation; and Figs. 3 and 4 are sections similar to Fig. 3, but illustrating different steps of the construction.

As illustrated, my present receptacle is made up of two half portions 1 and 2, the 40 heads 3 being of any desired construction. These portions are preferably of steel, the thickness depending upon the size and character of receptacle desired.

The two halves 1 and 2 are adapted to be 45 pressed or forced onto a reinforcing ring 4 which is provided with an annular rib 5 against which the edges 6 of the halves of the receptacle abut. This ring is preferably of heavier metal than the two halves and 55 the outer edges 7 of the ring are rounded or turned down to facilitate assembly as the

halves fit the ring tightly and are pressed or otherwise forced into position. The ring is also slightly curved or tapered from the rib to fit the curve of the barrel. 60

When the two halves are assembled on the ring as shown in Fig. 2, they are preferably spot or rivet-welded together at points 9 around the ring as shown in Fig. 3, although this welding is not essential and may be 65 omitted in certain forms of barrels.

After being thus welded together, the ring and barrels are welded along the rib, the extending portion of the rib being melted down to make a smooth finished 70 joint. This rib furnishes the necessary metal to fill the space between the ends of the receptacle to the desired point. In some cases the rib will supply the entire amount of the metal needed to make a joint such as 75 shown on the drawings, while in other cases a greater or less amount of metal may be used depending upon the exact form of joint to be produced. In any case, the rib will supply sufficient metal to effect a fusing or 80 flowing of the metal in the various parts.

It will be understood that the welding is preferably done by an electric arc or oxyacetylene flame and it may be desirable in some cases to add metal during the welding 85 operation.

It will of course be understood that the ring reinforces the barrel as well as making a satisfactory form of welded joint, and various forms of rings may be employed. 90 The radial rib is of importance as it centers the ring and allows the two halves to be forced tightly into position before welding. The rib also furnishes the required metal for making a smooth joint, and this rib 95 will take various shapes or be of various lengths, depending upon the thickness of the barrel and the strength desired.

By the present method a satisfactory and suitable barrel or receptacle can easily be 100 made and a barrel that is reinforced at the center. Any desired types of heads may be used and a smooth finished article is obtained.

Other forms may be employed embodying 105 the features of my invention instead of the one here explained, change being made in the form or construction, provided the elements stated by any of the following claims or the equivalent of such stated elements be 110 employed, whether produced by my preferred method or by others embodying steps

equivalent to those stated in the following claims.

I therefore particularly point out and distinctly claim as my invention:—

- 5 1. The method of making steel barrels and the like, consisting in forcing smooth-walled substantially cylindrical half sections over a reinforcing ring having an annular rib on its outer surface, and then homogeneously joining such sections and said ring by flowing the metal of such rib.
- 10 2. The method of making steel barrels and the like, consisting in forcing smooth-walled substantially cylindrical half sections over a reinforcing ring having an annular rib on its outer surface until such sections contact such rib, and then homogeneously joining such sections and said ring by flowing the metal of such rib.
- 15 3. The method of making steel barrels and the like, consisting in forcing smooth-walled substantially cylindrical half sections over a reinforcing ring having an annular rib on its outer surface until such sections contact such rib, spot-welding such sections to said ring, and then joining such sections and said ring by flowing the
- 20
- 25

metal of such rib toward and into homogeneous union with the contacting faces of such sections.

4. A metal barrel or the like comprising two open-ended substantially smooth-walled sections with their open ends adjacent each other, a reinforcing ring disposed within the adjacent edges of said sections and in snug contact therewith, and an exteriorly projecting rib on said ring interposed between the adjacent edges of said sections, whereby the heating of said rib to a flowing condition will effect a homogeneous union of said ring with said two sections.

5. A metal barrel or the like comprising two open-ended substantially smooth-walled sections with their open ends adjacent each other, a continuous reinforcing ring tapering slightly from the center and provided with an annular outwardly projecting rib slightly higher than the thickness of the sections, and said sections fitting snugly over said ring and against said rib, said rib being adapted to be flowed to homogeneously unite said sections and said ring.

Signed by me, this 15th day of Feb., 1919.
AGNAR KAARBO.
